UNITED STATES PATENT OFFICE.

JOSEPH J. CURRY, OF PHILADELPHIA, PENNSYLVANIA.

DESIGN FOR A KNITTED FABRIC.

No. 38,856.

Specification for Design.

Patented Oct. 8, 1907.

Application filed August 14, 1907. Serial No. 388,564. Term of patent 7 years.

To all whom it may concern:

Be it known that I, JOSEPH J. CURRY, a citizen of the United States, residing in Philadelphia, Pennsylvania, have invented a certain new, original, and ornamental Design for a Knitted Fabric, of which the following is a specification, reference being had to the accompanying drawing, forming part thereof, which shows a view in elevation of the ornamental design for knitted fabric constituting my invention.

I claim:

The ornamental design for knitted fabric as shown in the accompanying drawing.

JOSEPH J. CURRY.
